UNITED STATES PATENT OFFICE

132,139

DESIGN FOR A PICTURE FRAME

William J. Rothstein, New York, N. Y.

Application December 31, 1941, Serial No. 104,938

Term of patent 7 years

To all whom it may concern:

Be it known that I, William J. Rothstein, a native of Russia and a citizen of no country, residing at New York city, in the county of New York and State of New York, have invented a new, original, and ornamental Design for Picture Frames, of which the following is a specification, reference being had to the accompanying drawing, forming part thereof.

Figure 1 is a front elevational view of a picture frame, showing my new design; and

Figure 2 is a side elevational view of the frame. The characteristic features of my design reside in the portions shown in full lines.

I claim:

The ornamental design for a picture frame, as shown and described.

WILLIAM J. ROTHSTEIN.
